ATTORNEYS

UNITED STATES PATENT OFFICE.

EDMUND H. LUNKEN, OF CINCINNATI, OHIO.

WINDOW.

Application filed November 15, 1918. Serial No. 262,647.

To all whom it may concern:

Be it known that I, EDMUND H. LUNKEN, a citizen of the United States, and a resident of Cincinnati, in the county of Hamilton and 5 State of Ohio, have invented certain new and useful Improvements in Windows, of which the following is a full, clear, and exact description, reference being had to the accompanying drawing forming part of this specification.

My invention relates to what is known as pocket windows in which a pocket is provided in the upper portion of the sash frame for the reception of the sash to give a free 10 and unobstructed window opening.

In pocket windows of the kind under consideration, it has been customary to make up the window complete at the factory and form it into a package for shipment with 15 the sashes, frames and the glass all assembled, leaving nothing for the contractor to do but to wall them in and to surround the frame with the inside trim, which is usually of special wood to go with the remainder 20 of the interior woodwork.

Involved in this inside trim are the side stops and top bead for the sashes, and it is customary in the finish of an ordinary frame to set the side stops and top bead flush with 25 each other on the inner edges.

In the pocket window, however, if the top bead is applied in the usual way, it will project over the pocket opening and interfere with the free movement of the sashes when 30 raised into the pocket. In fitting the top bead, therefore, it has to be set with its inner edge out of line with the side stops and as a result, unless great care is taken, the top bead is apt to project slightly over the 35 pocket opening, or be applied at a slight angle and thus mar and rub the face of the sash as it is raised into the pocket.

A principal object of my invention, in the present instance, is to dispense altogether 40 with the usual top bead and to provide a construction which shall take the place of and prevent the attachment of the top bead, and at the same time which shall prevent 45 warping and stiffen the walls of the weight box and in other ways render the construction 50 more effective.

Another object of the invention is to provide a construction of parting strip which shall serve the purpose not only of the ordinary

nary parting strip, but shall also act as a 55 weather strip, and the construction is such that the free ends of the strip can be spread or separated to take up any looseness or undue play between the sashes.

Still another object of my invention relates to the means provided for forming a weathertight joint for the outside of the frame at the lower edge of the pocket in connection with the screens, in which interlocking metal strips are employed intermediate the frame and screens to engage and interlock when the screens are in place, to serve not only as weatherstripping but also to hold the upper screen properly in position, and in which provision is also made 65 for the easy removal of the top screen.

To improve the construction in connection with the installation of the inside trim and the interlocking strip for the screen on the outside, I make use of metal angle strips in 70 the manner to be hereinafter particularly pointed out and claimed, while for the parting strip I provide a wooden filler or core 75 encased in a copper strip, the construction being secured in place by clips, all in the manner and for the purpose hereinafter described and claimed.

In the drawing,

Figure 1 is a vertical longitudinal section of my improved window construction.

Figure 2 is a front elevation of the pocket window construction, with the upper corner partly in section.

Figure 3 is a perspective view of the angle strip employed for the top of the window 80 opening.

Figure 4 is a cross section of a portion of the window, taken on the line *a*, *a*, of Figure 1.

Figure 5 is a perspective view of a portion of the parting strip, showing also the clip for securing the same.

The pocket window is of the usual construction, provided with the upper and lower sashes 1, 2, with the meeting rails 3, 4, the 100 sashes being mounted in the side stiles 24 with the sill piece 7 and the head piece 8. Space is also provided adjacent the side stiles for the usual lower and upper window screens 41, 42. The sash stiles run to 105 the top of the pocket above the window opening and the head piece closes the pocket top. The front of the pocket is, in the construction

illustrated, formed of corrugated sheet metal 9 to which the plastering 10 is secured. The outer wall of the pocket is enclosed by sheeting 11 to which when the pocket window is 5 installed the weatherboarding 12 is secured.

With the framework finish 13 for the outside, on the inside the finish framework 14 is provided and the sill piece 15. The sashes are shown with the usual sash cords 10 16, 17, which run over the sash pulleys 18, 19, at the head of the pulley stiles. The window screens 41, 42, which run up into the pocket, have the channel bar guide 22 of a size to take both screen frames, and the 15 outer face of the top rail of the lower screen frame 41 is provided with an additional strip 21 to engage over the bottom rail of the upper screen, so that both screens may be drawn down together. This strip also 20 engages the upper bar of the upper screen frame, so that both frames may be pushed up together.

Inasmuch as the sashes run up for their 25 full length into the pocket when properly balanced, the user in raising the sash may lift it so rapidly as to strike with a considerable blow against the head piece. In order to prevent this for the inner sash and to furnish a brake and guide for the sash 30 within the pocket, I secure between the pulley stile 24 and the pocket casing, a strip of sheet metal 25 running vertically up into the pocket with its free edge 26 curved over to form a bearing for the sides of the 35 sash and serve as a brake and guide therefor. In attaching the side stop 27 for the inner sash, the inner edge of the stop is secured on a line with this guide strip.

As heretofore referred to, for the 40 purpose of preventing the attachment of the usual top bead, I provide a metal angle strip 28, which is secured along the lower edge of the cross board 29 of the pocket construction, with the lower edge of the 45 angle strip flush with the inner edge of the cross board. The strip being of metal acts as a finish for the upper end of the sash opening and by reason of its being a metal strip prevents the attachment of a top bead. 50 At the same time this angle strip extending as it does across the entire width of the pocket construction, strengthens very materially the pocket and prevents warping, and binds the walls of the weight boxes 55 together.

For the outside of the frame I also provide an angle strip 52, which similarly strengthens the construction and prevents warping on the outside.

60 Heretofore in order to provide a weather-tight joint between the top rail of the upper screen and the pocket casing, I have made use of felt material, which is not entirely satisfactory, and in order to hold the top 65 screen in place and prevent its dropping

down, I have been obliged to use spring pins, or other means for locking the screen in position.

As a much simpler and more effective method of obtaining these results, I now 70 utilize the strip 52 to secure across the top of the outside opening a strip 43, between which and the lower edge of the sheeting I secure a strip of sheet metal 44 with an upturned flange. 75

Secured on the top rail of the screen is a corresponding sheet metal strip 47 with a downturned flange. When the window screen is in its normal position in the frame, the two flanges of the metal strips interlock and furnish a much more satisfactory 80 weathertight closure than the felt material heretofore used.

The strip 47 is secured in place on the screen by the filler strip 46, which in my 85 former construction has been employed to stiffen and strengthen the upper screen rail and to form the bearing for a weather-strip when the window is closed and which has extended the width of the screen into 90 the screen guides. In the present construction, this filler strip is cut off at the ends and does not extend into the channel guides, and as the metal strip is also cut away at the ends so as not to interfere with the 95 screen guides, the upper screen, while normally held by the interlocking flanges, can readily be detached when desired by merely raising the screen to separate the flanges, then pushing over the screen toward the 100 sash and permitting the flanges to pass each other.

The window upper rail 2 for a wiping strip against the screen frame is shown 105 equipped with a wood strip 53, which carries a felt piece 54. This felt piece is arranged to touch the screen frame piece 46 when the upper sash is in normal closed position.

To serve as a parting strip between the 110 sashes, I provide the filler 30, preferably of wood, and encase this strip on three sides in a sheet metal casing 31. The free edges 32 of this casing extend outwardly from the pulley stile and bearing against the sides 115 of the sashes serve as a very effective weatherstrip. To take up any looseness of play between the sashes, the free edges of the casing can be readily spread apart slightly, so as to maintain a bearing on the 120 sashes.

In order to secure the parting strip in place in the vertical groove in the pulley stile, I provide the clips 33 which are folded around the back of the parting strip and 125 have the projecting flanges 34, 34, which are screwed or otherwise secured to the pulley stile on each side of the parting strip. To hold the wood filler in its sheet metal casing and to hold the clips at the proper 130

point, I prefer to rivet the clips as indicated at 35 in Figure 5.

Having thus described my invention, what I claim as new and desire to secure by Letters Patent, is:—

1. In a pocket window construction, a window frame with sashes therefor, and a wall pocket adjacent the window opening for the reception of the sashes, and a sheet metal strip forming a continuation of one of the side stops, clamped between the edges of the stile and the inside pocket wall, extending into the pocket and with its outer edge curved over to form a brake and guide for the sides of the lower sash when raised into the pocket.

2. In a pocket window the combination with a wall pocket portion at one end of the frame of said window, of a channel for a screen running into said pocket, a screen adapted to slide in said channel and having a frame of a thickness less than the width of the channel, and normally interlocking strips at the mouth of the wall pocket and on the frame of the screen, whereby the screen is held in place with its upper end in the mouth of the pocket, the relative dimensions of said screen and said channel

permitting the second mentioned strip to be moved past the first mentioned strip after 30 said strips are disengaged by raising said screen.

3. In a pocket window the combination with a wall pocket portion at one end of the frame of said window, of a channel for a screen running into said pocket, a screen adapted to slide in said channel and having a frame of a thickness less than the width of the channel, and normally interlocking strips at the mouth of the wall pocket and 35 on the frame of the screen, whereby the screen is held in place with its upper end in the mouth of the pocket, the relative dimensions of said screen and said channel permitting the second mentioned strip to be 40 moved past the first mentioned strip after said strips are disengaged by raising said screen, a sliding window sash in said frame, said sash having a weather strip projecting into the path of the screen, whereby said 45 weather strip may contact with the screen frame when the strips are in interlocked position in the pocket mouth, and the sash arranged with the stripped portion in the pocket mouth.

EDMUND H. LUNKEN.
